UNITED STATES PATENT OFFICE.

PETER GIGLIO, OF NEW YORK, N. Y.

HOLDING DEVICE FOR VIBRATORS.

1,269,421.

Specification of Letters Patent. Patented June 11, 1918.

Application filed September 17, 1914, Serial No. 862,173. Renewed November 24, 1917. Serial No. 203,864.

To all whom it may concern:

Be it known that I, PETER GIGLIO, a citizen of the United States, and a resident of the city of New York, Ozone Park, borough 5 of Queens, county of Queens, and State of New York, have invented a new and Improved Holding Device for Vibrators, of which the following is a full, clear, and exact description.

10 This invention relates to improvements in holding devices for vibrators, and has for an object to provide an improved construction whereby the device may be readily clamped to the hand so as to transmit all of 15 the vibrations from the vibrator to the hand.

Another object of the invention is to provide a holding device with a clamping pad and adjustable members for causing the pad to grip the hand.

20 A further object of the invention is to provide a holding device formed with partially encircling members or arms associated with a screw adjusting structure for clamping a hand firmly in place.

25 A still further object of the invention is to provide a simple, strong, and comparatively cheap construction in which a single clamping piece may be utilized for causing the holder to firmly grip the hand without 30 injury thereto.

In the accompanying drawings—

Figure 1 is a perspective view of a holder embodying the invention, the same being shown supported by a hand;

35 Fig. 2 is a side view of a vibrator and power shaft together with a holder embodying the invention secured to the vibrator;

40 Fig. 3 is an enlarged side view of the holder shown in Fig. 1, part of the same being broken away for better illustrating the construction;

Fig. 4 is a top plan view of the structure shown in Fig. 3;

45 Fig. 5 is a bottom plan view of one end of the clamping pad and associated parts;

Fig. 6 is a top plan view of the structure shown in Fig. 5;

50 Fig. 7 is a side view of the device shown in Fig. 3 with the parts arranged in a clamped position;

Fig. 8 is a section through Fig. 7 approximately on line 8—8;

Fig. 9 is a side view of a slightly modified form of the invention.

55 Referring to the accompanying drawings by numerals, 1 indicates a holder as an en-

tirety, which holder is connected with the vibrator 2 by any suitable means, as for instance by having a set screw arranged in the post 3, which set screw clamps a projection arranged on the casing of the vibrator 2. Extending into casing 2 is a flexible shaft which is connected with the operating mechanism of the casing 2 so as to actuate the same whenever desired. The device is 60 intended to be placed upon the hand as shown in Fig. 1 and thereby vibrate the hand including the fingers and thumb, which vibration is transmitted to the patient when the hand is brought into contact 65 with him. The holder 1 is formed with a body 4 preferably formed of metal, which body has a turned-over side 5 and a removable side 6. The body 1 is formed with a pair of upstanding posts 7 and 8 and a 70 pair of encircling arms 9 and 10. Arranged in the body and the encircling arms 9 and 10 is a clamping member 11 formed of felt or other suitable material designed to 75 conform to a greater or less extent to the contour of the hand. Rigidly connected to the ends of the clamping member 11 are flexible clamping bands 12 and 13, the same being connected in any desired manner, as for instance by stitching 14. It will be observed 80 that the ends of the bands 12 and 13 are turned over for providing what may be termed caps 15 and 16, which slidingly fit over the ends of the arms 9 and 10. Normally the caps 15 and 16 are arranged as 85 shown in Fig. 3 with their ends spaced a short distance from the ends of the arms, or if a comparatively large hand is inserted the ends will move against the ends of the arms so as to accommodate the hand. If 90 the hand is comparatively small the ends will remain as shown in the drawing, and the flexible bands 12 and 13 will act against the caps from that position in clamping the hand in position. The upper ends of the 95 flexible bands 12 and 13 are formed with spaced eyes 17 as shown in Fig. 6, which eyes accommodate pintles 18 and 19, which pintles not only extend through the respective eyes mentioned but also through eyes 100 20 and 21 formed on the traveling nuts 22 and 23, which traveling nuts are rounded or beveled at 24 and 25, respectively, so as to ride over the clamping member 11. The nuts 22 and 23 are provided with right and 105 left threads, respectively, one thread being larger than the other so that one nut will

travel faster than the other. Preferably nut 22 is caused to travel slower than nut 23 as it is desirable to give a greater movement to that part of the clamping member 5 11 arranged on the thumb side of the hand. In order that the nuts 22 and 23 may properly travel a shaft 26 is provided formed with threaded sections 27 and 28, the threads on section 28 having a greater pitch than 10 the threads on section 27 so that nut 23 will travel faster than nut 22. The shaft 26 has one end journaled in the post 7 and the opposite end supported by a journal pin 29 extending into a suitable bore in the end of 15 the shaft, pin 29 being supported by post 8 and rotated by a suitable thumb member 30. A suitable set screw or pin 31 is provided for connecting the journal pin 29 rigidly with shaft 26.

20 It will be noted that the body 4 is provided with suitable enlargements for receiving threaded apertures so that the clamping screws 32 may be used for clamping side 6 in position as shown in Fig. 3. 25 The eyes 20 and 21 are turned substantially at right angles to the remaining part of the nuts 22 and 23 so that they may fit into the corners 33 and 34, respectively, when the nuts 22 and 23 are moved as far 30 apart as possible. When the parts are in this position the hand may be thrust between the arms 9 and 10 and then the holder clamped to the hand upon a proper rotation of the thumb member 30 which will gradually bring the nuts 22 and 23 toward each 35 other and operate the flexible members 12 and 13 so that these members will press the felt clamping member 11 tightly against the hand. It will be noted that the body 4 is provided with a slot 35 through which the traveling nuts 22 and 23 project, the same being shown more clearly in Fig. 4. Also, a post 3 is preferably formed integral with body 4, which post is provided with an 40 aperture 36 through which a support for the vibrator 2 is passed, which support is clamped rigidly in place by set screw 37.

45 In Fig. 9 will be seen a slightly modified form of the invention in which the shaft or bar 26' is provided only with one threaded portion 38 as there is only one nut 39 used which is connected with a flexible strap 13', and is designed to operate in a similar manner to the way the strap 9 of the preferred 50 construction operates. From this construction and arrangement it will be seen that either a single clamping arrangement may be used or a double clamping arrangement may be used as shown in Fig. 7. It will be 55 noted that in Fig. 7 as well as the remaining figures of the preferred form means are provided for causing strap 13 to move faster than strap 12. It will also be noted, especially from Fig. 1, how the members 9 and 60 10 fit the hand. Member 9 fits around be-

tween the thumb and first finger and extends toward the rear of the palm of the hand. Member 10 also extends toward the rear of the palm of the hand so as to not pinch or injuriously affect the hand when 70 the fingers are folded in. If members 9 and 10 extended directly toward each they would prevent an easy closing of the hand, and consequently cause the hand to become tired quickly. By arranging these members 75 below the turning or pivotal point, as it were, of the hand, no objectionable effect is produced on the hand when the device is gripped therein. This is of considerable advantage as the fingers and hand must be 80 moved considerably during the massaging of the person and when so moving the vibrator naturally causes a more or less vibration which is transmitted through the hand to the patient.

85 What I claim is—

1. A holding device for vibrators comprising a body formed with a pair of inclosing arms, clamping means arranged in said body designed to clamp a hand to said body, means designed to move transversely of the hand for operating said clamping means, and a rotatable member operating said transversely movable means.

2. In a holder of the class described, a body designed to be arranged to extend transversely of the hand in operation, a slot arranged longitudinally of the body, a pair of arms arranged at each end of the body, said arms describing approximately half of a circle, a pair of flexible members arranged in said body, one member being arranged adjacent each arm, a traveling nut connected with each of said flexible members, said traveling nut projecting through said slot, and a threaded shaft engaging said nuts for moving the same whereby they cause said flexible members to clamp the hand arranged in said body.

3. In a holder for vibrators, a body, means for connecting the body with a vibrator, a pair of flexible encircling members arranged adjacent the ends of said body, a clamping member designed to be contracted by said flexible members so as to grip the hand of an operator, a pair of traveling members designed to travel toward and from each other, means for connecting said traveling member with said flexible encircling members, and manually operated means engaging said traveling members for holding the traveling members in any desired adjustment.

4. In a holder for vibrators, a body formed with a pair of encircling arms, a pair of flexible clamping members arranged in said arms, a clamping pad arranged in said arms and said body, said flexible clamping members encircling the ends of said pad, a pair of traveling nuts connected with said

- clamping members and a threaded shaft engaging said nuts for moving the same toward and from each other, the threads on said shaft and in said nuts being arranged 5 right and left so that upon a rotation of the shaft in one direction the traveling nuts will be moved toward each other, and when the shaft is moved in the opposite direction the traveling nuts will be moved away from 10 each other.
5. In a holder for vibrators, a body provided with a pair of encircling arms, a flexible clamping member arranged in each of said encircling arms, a clamping pad de- 15 signed to be contracted by said clamping means, a traveling member connected with each of said clamping members, said travel- 20 ing members being formed with oppositely pitched threads, a shaft with oppositely pitched threads engaging said traveling 25 members for moving the same toward and from each other, the threads extending in one direction being of a greater pitch than the threads extending in the other direc- 30 tion, whereby one of the traveling members will move faster than the other.
6. In a holding device for vibrators, a body, clamping means, a pair of traveling nuts secured to said clamping means for 35 moving the clamping means toward each other and away from each other, said nuts being formed with apertures threaded in opposite directions and with different pitched threads, a shaft threaded at each 35 end for engaging the respective nuts, and means extending from said body acting as
- supports for said shaft whereby when said shaft is rotated in one direction said nuts will be moved toward each other, one nut traveling faster than the other, and when 40 said shaft is moved in the opposite direc- 45 tion said nuts will move apart, one nut traveling faster than the other.
7. In a holder for vibrators, a rigid body formed with a pair of converging encircling arms, a flexible clamping member arranged 50 on one of said arms, a clamping pad ar- 55 ranged on said arms and said body, said flexible clamping member encircling part of said body, a traveling nut connected with said clamping member, and a threaded shaft 60 engaging said nut for moving the same to- 65 ward and from a clamping position.
8. In a holder for vibrators, a rigid body formed with a pair of encircling arms, one 55 of said arms engaging the palm of the hand adjacent the thumb and partially encircling the thumb, the other of said arms engaging the palm of the hand opposite said thumb and converging with said first mentioned 60 arm whereby both of the arms are positioned away from the bending point of the hand when the hand is closed, and means for 65 clamping said body to said hand, said means being connected with one of said arms.

In testimony whereof I have signed my name to this specification in the presence of two subscribing witnesses.

PETER GIGLIO.
